UNITED STATES PATENT OFFICE.

ARTHUR F. POOLE, OF PELHAM MANOR, NEW YORK, ASSIGNOR TO REMINGTON AC-
COUNTING MACHINE CORPORATION, OF NEW YORK, N. Y., A CORPORATION OF NEW
YORK.

CALCULATING MACHINE.

Application filed October 21, 1922. Serial No. 595,925.

To all whom it may concern:

Be it known that I, ARTHUR F. POOLE, citizen of the United States, and resident of Pelham Manor, in the county of Westchester and State of New York, have invented certain new and useful Improvements in Calculating Machines, of which the following is a specification.

This invention relates to calculating machines and it has for its object to provide certain improvements in that class of machines. One of the principal objects of the invention is to provide, in a calculating machine in which the register wheels are operated or controlled by a series of denominational racks, for a positively acting transfer mechanism capable of acting while the register wheels are in gear with said racks and capable of acting in both directions for plus and minus calculations, and is in the nature of an improvement on the transfer mechanism disclosed in the application of R. H. Strother, filed August 21, 1922, Serial No. 583391.

Another object is to provide a registering unit or totalizer of the sort just referred to and which is also of such kind that a plurality of such totalizers can, if desired, be arranged along a set of elongated racks so that the same racks can be used for registering in different totalizers or registers.

The invention also has other objects which will appear in the course of the following description.

To the above ends the invention consists in certain features of construction and combinations and arrangements of parts, all of which will be fully set forth herein and particularly pointed out in the claims.

Some of the features of the invention are of such character that they can be modified considerably. One embodiment of the invention is illustrated in the accompanying drawings in which

Figure 1 is a front to rear vertical section through the machine about on the line 1-1 of Figure 2.

Figure 1^a is a continuation of Figure 1 toward the right, the rear part of the machine being broken away in said Figure 1.

Figure 2 is a plan view in section on line 2-2 of Figure 1.

Figure 3 is a front elevation of the upper part of the totalizer, most of the figure being in section on the line 3 of Figure 1, the sec-

tion extending to the bottom of the carrying wheels 36.

Figure 4 is a right-hand side elevation on a smaller scale than the other drawings.

Figure 5 is a transverse section through 60 the swinging part of the register on the line 5-5 of Figure 1 and looking toward the rear.

Figure 6 is an isometric view of a portion 65 of the transfer mechanism.

The present invention relates chiefly to the totalizer or registering mechanism and the transfer mechanism, and the actuating mechanism has therefore been shown only in a very much simplified form. It will be 70 understood that said actuating mechanism may be elaborated and the racks extended to accommodate a number of registers, only one of which is shown in the drawing.

The frame or support for said actuating 75 mechanism comprises a base block 10 having cut in its upper face grooves 11 in which rack bars 12 are arranged to slide front and back. Said rack bars are the devices which actuate the register in the sense that they 80 drive the register wheels, and they are also the devices which control the register in the sense that they determine the extent to which said wheels turn, and, therefore, the number that shall be registered on said 85 wheels. Other forms of actuating devices and controlling devices may be employed.

In the present instance these rack bars are shown only long enough to actuate one register but said bars may be made longer if desired so that a plurality of independent registers can be operated by them, said registers being arranged one in front of another along the racks. Any suitable means can be 90 provided for imparting differential motion 95 to these rack bars, such means having been designed in a great variety of forms well known in the art. In the present instance each of them is merely shown with a handle 13 projecting upward from its forward end

through a slot 14 in a cover plate 15, which cover plate is secured as by screws 19 to the base block 10. Each handle 13 may have a pointer 16 bent off therefrom and co-operating with a series of graduations 17 suitably numbered. The machine shown being arranged for decimal calculation these graduations are numbered from "0" to "9" inclusive. The racks are restored to and normally held in their rear positions by means 100 105 110

of springs 18, each hooked into the rear end of a rack bar and said springs at their rear ends being connected to a cross bar 20 suitably supported in arms of sheet metal frame pieces 21, which frame pieces are secured by screws 22 to the sides of the block 10 from which they project upward and rearward. The rearward motion of said rack bars may be limited by any suitable means as by the rear ends of the slots 14 or by stops 23 provided for the purpose. The racks 12 are drawn forward by hand by manipulating the handles 13 to any desired extent to represent the digits of a number to be registered, and they are temporarily retained in their forward positions by any suitable means, that here shown consisting of a series of pawls 24 pivoted on a shaft 25 and pressed upward by springs 26 into engagement with a series of ratchet teeth 27 on the under side of the several racks. In order to accommodate this pawl mechanism the block 10 has a transverse cut-out 28 in the under-side thereof, which cut-out may be covered by means of a plate 30 extending across the bottom of the cut-out and bent up at its ends and secured to the block 10 by means of screws 31, Fig. 4. The shaft 25 is journaled in the upstanding ends of this plate and the springs 26 bear against the horizontal part of the plate. In order to release the pawls when it is desired that the racks be restored by their springs 18, each of said pawls is made with a depending arm 29 and a yoke or bail bar 32, mounted in arms 33 fixed on the shaft 25, extends across said depending arms so that if said shaft be rocked clockwise in Figs. 1 and 4 all of the pawls will be depressed to release the rack bars. The shaft 25 projects at one end beyond the plate 30 and has a hand crank 34 thereon by means of which it can be operated whenever desired. It will of course be understood that the mechanism thus far described can be varied and much elaborated, the essential thing for the present case being a set of racks 12 with means for moving them differentially first in one direction and then in the opposite direction.

The registering and transferring mechanism actuated by the racks 12 comprises in each denomination a transmitting gear or pinion 35 which in the present instance meshes directly with the rack 12; a carrying gear 36 meshing with the pinion 35 on the side thereof opposite to the rack 12; an idler pinion 37 driven by the carrying gear 36; and the pinion 38 of a dial wheel 40, said pinion driven by said gear 37; and also a so-called Geneva wheel 41 driven by said carrying gear 36.

It may aid in reading the drawing to say at the outset that gear 36 is hidden in Fig. 1 by a certain gear 58 having the same peripheral outline, said gear 58 meshing with

certain sector teeth 57. Parts 57 and 58 will be described hereinafter.

The wheels 36 are strung along a shaft 42, the wheels 37 along a shaft 43 and the dials 40 along a shaft 44 all of said shafts being supported at their ends in a register frame 45 comprising side plates 46 secured together partly by the shafts referred to and partly by other frame rods, two of which have been numbered 47 on the drawing. 75 These rods may be secured in said frame plates by means of screws which for the purpose of identification have been designated by the same numbers as the respective shafts and rods. The side plates 46 at their lower rear corners are pivoted by means of a rod or shaft 48 in the stationary frame plates 21, so that the frame 45 may be rocked about said pivot to lift the gears 36 out of mesh with the gears 35 in order in each 80 calculation to have the register wheels disconnected from the rack during the motion of said racks in one direction as is well understood in calculating machinery. By a modification of the mechanism this disconnection could be effected between the racks themselves and the pinions 35 but in the present instance I have preferred to effect it between said pinions 35 and the gears 36. 85 In order to limit the downward movement 90 of the register frame 45 each of the side plates 46 has a foot 50 which, when the parts are in engaged or operative position, rests on a portion of the base framework.

In the present simplified actuating mechanism, the frame 45 is raised and lowered by hand. Said frame may and preferably does have a cover plate which however is not shown in the drawing. 100

The transfer or carry from one denomination to another is effected by moving or displacing the axis of one of the pinions 35 in the plane of said pinion and in a direction contrary to that of the motion of the rack 12. When this is done the pinion 35 pivots 110 on said rack 12 so that the tooth at the upper side of the pinion which is in engagement with the wheel 36 moves twice as far as the axis of the wheel 35. To this end each of said wheels 36 except the one of lowest order is mounted on an individually movable support 51, Figs. 1, 5 and 6, the wheel being journaled on a stud 52 riveted in and projecting leftward from said support. The support 51 is pivoted at its lower end on a stud 53 projecting leftward from a frame, bracket or hanger 54, said hangers and the lower ends of said movable supports lying between the racks 12 as shown. The series of brackets 54 are here shown mounted on a pair of frame rods 55 secured at their ends in the frame pieces 21, the brackets being spaced apart by washers 56. In the machine from which the present drawings were made the numerals are so 125 130

disposed on the dials 40 that when the register is in gear, motion of the racks 12 toward the front of the machine causes subtraction and motion of said racks towards the rear causes addition. If during the process of addition one of the supports 51 be swung about its pivot 53 toward the front of the machine, that is to say, in a direction contrary to that of the motion of the rack 12 for addition, the bearing 52 will be moved a half space forward and the upper part of the wheel 35 will be moved one space forward and will therefore add one on the carrying wheel 36 to which it is geared; and this will occur whether the rack 12 of the higher denomination is stationary at the time or whether it is in motion. If during the process of subtraction it is necessary to carry or transfer to one of the register wheels this is effected by moving the support 51 in the opposite direction, namely, toward the rear.

In order positively to operate the supports 51 of any denomination from the carrying wheel 36 of the next lower denomination various devices can be provided. In fact this function can be performed by mechanism in quite a variety of forms of which that shown in the drawing is one instance: As shown in each of said supports is prolonged upward and formed with three teeth 57 at its upper end, so that said support is in the form of a segment gear or sector. Said teeth mesh with gear wheels 58 journaled on the shaft 42 in alternation with the carrying gears 36. Said gears 58 are of the same diameter and have the same number of teeth as said gears 36, both being thirty toothed gears. This being so, the teeth 57 of the segmental support 51, have their pitch line tangent to those of the gears 35 and 36, and the axis of the pivot 53 is in the pitch line of the racks 12. These proportions can, of course, be varied.

It may be a sufficient description of the wheels 36, 37, 38, 40 and 41 to say that in the specific machine from which the drawings were made these parts are identical with parts occupying somewhat similar positions in the Wahl calculating mechanism constituting part of the well known Remington accounting machine, which has for a number of years been in extensive use. Each of the carrying gears 36 is made in three planes or strata; the right-hand one of which is an ordinary thirty toothed gear; the middle plane has but three teeth 60 shown in dotted lines in Fig. 1 and adapted every time the carrying gear passes the space between its "9" and its "0" position to engage a ten toothed pinion 61, Fig. 5, constituting the right-hand plane of one of the Geneva wheels 41. The left-hand plane or layer of the wheel 36 is of less diameter than the other two and is of cylindrical form except

that opposite each of the teeth 60 of said layer or plane has a peripheral depression or cut-out 62, Fig. 1. The Geneva wheel has a large scalloped part which normally rides on the smooth part 63 of this section 70 and which is thereby locked against rotation, but rotation of said Geneva wheel to the extent of one tooth is permitted by the cut-out 62 every time one of the transfer teeth 60 engages a tooth of the pinion 61. 75 This form of intermittent gearing is so well known in the art that it need not be further described except to say that the Geneva wheel 41 has also a left-hand plane or stratum 64 consisting of a ten toothed pinion 80 which in the Wahl mechanism engages the thirty toothed part of the next higher carrying wheel 36. In the present machine this section of the Geneva wheel engages the gear 58, which gear at its lower side meshes with 85 the support 51 of next higher denomination. The construction is such that when any wheel 36 passes from "9" to "0" or from "0" to "9", it turns the Geneva wheel one tooth space which turns the next succeeding gear 58 one tooth space in the same direction that the carrying wheel 36 is turning; and said gear 58 rocks the support 51 of the next succeeding denomination one tooth space in the same direction that the carrying wheel is turning and thus transfers to said next denomination, as described.

The Geneva wheels 41 may be mounted on a transverse rod or shaft the same as the other pinions but as it is important that these pinions engage the carrying wheels 36 with considerable accuracy they are preferably mounted on individual adjustable supports 65, each of which has a stud 66 projecting therefrom on which a Geneva pinion 100 is journaled. Said supports 65 consist of arms having hubs mounted on transverse rod 67 suitably secured in the side plates 46 of the pivoted register frame 45. Each of said arms projects upward beyond its pinion, its upper part lying between two adjusting screws 68, which screws are threaded through transverse frame bars 70, the ends of which are mortised into the side plates 46. By adjusting these screws each Geneva pinion can be brought with precision into engagement with its carrying wheel. One of the bars 70 may have a slotted flange 71 to guide the supports 65 right and left. Springs 72 are shown each drawing the upper end of one of the supports 51 toward the front of the machine. These are not essential but are convenient in the process of adjustment, enabling the rear screw 68 to be left loose while the adjustment is being effected by the forward screw against which the spring keeps the support constantly pressed. After the adjustment is made the rear screw can be brought up snug to retain 120 the support positively in place.

After a registering operation, it is necessary to restore the supports 51 to normal position. In the present instance said supports have a normal middle position from which they are displaced toward the front of the machine for addition and toward the rear of the machine for subtraction. Each of said supports has a forwardly projecting arm having therein a V-shaped notch 73, the bottom of said notch being made with straight sides to receive a transverse bail rod 74 which is mounted at its ends on arms 75 pivoted at 76 to the base-block 10. This bail is adapted to be swung forward to an inoperative position shown by full lines in Fig. 1 and backward to an operative position shown by dotted lines. In operative position said rod occupies the straight-walled bottoms of all of the V-notches 73 and accurately locates all of the supports 51 in their normal middle position. In Fig. 1 these supports are shown in such normal middle position in full lines but one of them is shown by broken lines rocked forward for additive transfer. Whether the support was rocked forward in addition or rearward in subtraction the bail 74 would center it. This operation of restoring the transfer supports 51 is of course effected while the frame 45 is in its upper or inoperative position and the carrying gears 36 are out of gear with the pinions 35 and the gears 58 out of mesh with the segments 51, 57. Any suitable means can be provided for swinging the bail 74 at the proper time. In the simplified form of actuating mechanism shown in the present case one or both of the arms 75 is provided with a finger piece or handle 77 by which the bail can be worked at the proper time manually.

In the present machine the register wheel of lowest order is never actuated by transfer and it is therefore unnecessary that its pinion 35 be mounted on a movable support. In this machine therefore the stud 52 for the right-hand pinion 35 is secured not in a movable support but in a special hanger 78, Figs. 4 and 5, secured on the same rods 55 as the brackets 54. It is this stationary hanger 78 which serves as a stop for the right-hand foot 50 of the register frame 45. It will be noted, however, that in all denominations that are receptive to transfer the wheels 35 are mounted on movable supports.

In the form in which the invention is here shown the studs 53 on which the supports 51 are pivoted, have no heads, said supports being simply set on the projecting studs and motion leftward off of each stud being prevented by the devices to the left of said support. At the extreme left-hand end of the system there is a bracket 80 similar to the bracket 78 and having riveted thereto a washer 81, Fig. 5, which ultimately pre-

vents leftward motion of the last one of the supports 51. Each of the studs 52 has an enlarged head 82 and it is this head of the last stud to the left which abuts against the washer 81, Figs. 2 and 5. 70

The general mode of operation of the machine will be understood from what has been said, but this may be said additionally:—If it is desired to add a number on the register, the frame 45 is first rocked to the position shown in broken lines in Fig. 4 to disconnect the gears 36 from the gears 35. The rack finger-pieces 13 are then drawn forward each to an extent depending on the digit to be added in that particular denomination, and the racks are held forward by the pawls 24. The frame 45 is then depressed to its operative position shown in Fig. 1 and the bail 74 is drawn forward to its inoperative position shown by full lines in said figure. The hand crank 34 is then operated to release all of the pawls 24 to allow the racks 12 to be drawn back to normal position by their springs 18. In this operation the register wheels are turned additively each to an extent depending on the initial forward setting of its rack 12. In case any carrying wheel 36 passes from its "9" to its "0" position it will impart rotation counter-clockwise to a Geneva wheel 41 which will rotate the gear 58 to the left of said carrying wheel clockwise one tooth. This gear will rock the support 51 of the next higher denomination one tooth toward the front of the machine to the position indicated in broken lines in Fig. 1, and this operation will impart an increment of motion to the next carrier wheel 36 equal to one tooth of said wheel. After the registering operation is completed the operator will again rock the frame 45 to its disconnecting position and will then swing the bail 74 to its rear position, thus restoring any supports 51 and pinions 35 that may have been displaced. The machine is then ready for another operation. 100 105 110

In case it is desired to subtract a number the frame 45 is depressed to its operative position shown in Fig. 1, the bail 74 is drawn forward to its inoperative position, and the several racks 12 are then operated manually by their finger pieces 13 each to the appropriate extent. This at once turns the register wheels in directions the opposite of those that they turned in the case of addition. In case of transfer the Geneva wheels 41 and wheels 58 are also turned in the opposite directions from those of addition with the result that the appropriate support or supports 51 are rocked rearward with the same result as in addition but in the opposite direction. After the number has been subtracted the frame 45 is raised to its disconnecting position, the bail 74 is moved rearward to restore any displaced transfer 120 125 130

supports and the hand crank 34 is operated to release all of the racks 12 and to allow them to return idly to normal position under the influence of springs 18.

5 It will be noted that each of the gears 35, in the form of the invention shown, rocks back and forth from and to a definite normal position so that, if this gear were of greater diameter than here shown, it need 10 not have a complete set of teeth extending clear around it. This gear is in the nature of a lever which, when registering a digit, acts as a lever of the first order and which, when transferring, acts as a lever of the 15 third order.

In this form of positive transfer mechanism, as in all transfer mechanisms that operate by intermittent gearing, there is a certain amount of lost motion, with the 20 result that in case it is necessary to transfer through a number of wheels at a time as through a long row of nines in addition or of zeroes in subtraction, the wheels of higher order will lag, producing what has become 25 known as a "spiral" in the transfer mechanism. It is therefore desirable to provide means for aligning the wheels after each registering operation. In the present instance the spiral would show not only on 30 the register wheels but also on the pivoted supports 51, the first of which in a long carry would be approximately fully operated, the next one not quite so fully operated, the third a little more out of correct position, 35 and so on.

Means can be provided in a variety of forms for aligning or removing the spiral from these parts. In this machine if the 40 pivoted supports 51 be trued up that will of itself bring the register wheels to correct position. Two forms of aligning or spiral removing mechanism are shown in the present machine, one being spring operated and the other positively operated. Of these the 45 positive operation is preferred for the reason that it is considered to be more reliable.

The positively acting aligning or spiral removing mechanism shown in the drawing comprises a series of pointed or beveled 50 plungers 83 mounted for up and down sliding motion in suitable holes in two frame bars 84 mounted one above the other above the wheels 36 and 58. Each of said plungers has a pointed lower end adapted to be 55 pressed down into an interdental space in one of said gears 58 as shown in Figs. 1 and 3 to true up the said gear exactly to its correct position. As shown in Fig. 3 each of these plungers not only engages a gear 58 60 but it also engages the thirty-toothed part of the wheel 36 next to the left of said gear 58 and which is turned by a turning of said gear 58. The engagement of these plungers 65 with both the gears 36 and 58 is not essential, however, as the mechanism would be

lined up well enough by merely truing up either one of said sets of gears; but it is useful because by that means said plungers not only serve as spiral removing devices but they also serve as locks for the registering gear train when the register frame is in its elevated position. ⁷⁰

Any suitable means can be provided for elevating the plungers 83 to unlock the registering mechanism and for depressing said 75 plungers successively beginning at the right-hand end of the series. The means shown in the drawing for this purpose comprises a shaft 85 having spirally arranged eccentric parts engaging the plungers 83. In the present instance, these parts are produced by providing a spiral rib 86, projecting from the shaft, 85, said shaft and rib passing through openings in said plungers to provide room for which openings said plungers ⁸⁰ are widened front and back as shown in Fig. 1.

In said Fig. 1 the plungers are shown in their depressed position and the lower wall 87 of each of the openings in the looped portions of the plungers 83 is in that position concentric with the shaft 85 so that every one of said plungers has this lower wall engaged by the spiral rib 86 which positively holds the plungers down. The plunger at ⁹⁵ the extreme right of the series has in this position of the parts its wall 87 engaged by the rib 86 at the extreme rear end of said wall and the plunger at the left of the system has its wall 87 engaged by said rib at ¹⁰⁰ the front end of its wall, and intermediate plungers have their walls 87 engaged by said rib at intermediate points. This concentric wall of the plunger opening is, however, engaged by said rib in every one of the plungers ¹⁰⁵ so that they are all held down. If the shaft 85 be rotated clockwise in Fig. 1 the plunger at the extreme left will be elevated almost immediately by the engagement of the spiral with the upper wall 88 of the opening in said plunger. The next plunger will remain in its lower position until the spiral reaches the point where the forward end of the wall 87 joins the forward end of the wall 88 whereupon the second plunger ¹¹⁰ will be elevated, and so on across the series. The shaft is so moved prior to a registering operation. At the end of such operation and before moving the frame 45 to its upper disconnecting position the shaft is rotated ¹¹⁵ back counter-clockwise to its Fig. 1 position. In this rotation the right-hand plunger will be operated first, the second one thereafter, and so on, throughout the series. The upper wall 88 of the opening in each plunger is ¹²⁰ made in the arc of a circle, which circle is concentric with the shaft 85 when the plunger is in its upper position. In short, the centers of the two arcs 87 and 88 are apart ¹²⁵ a distance about equal to the extent of mo- ¹³⁰

tion of the plunger. It will be perceived that when the shaft first begins to rotate, the plunger at the end of the series will immediately be moved upward to the extent 5 of its motion until the center of the arc 88 reaches the center of the shaft 85 after which further rotation of the shaft has no further effect on that plunger. At this instant the next plunger begins to move and after it 10 the next, and so on; and the same thing occurs in opposite order when the shaft is rotated in the opposite direction. The rear wall of the opening in each plunger may be made a straight line as shown in Fig. 1.

15 In operation the shaft 85 and plungers 83 normally occupy the position shown in Fig. 1 where all of the gears in the register frame 45 are positively locked in proper position, and it remains in this position 20 until the frame 45 is turned down to its connecting position. The shaft is rotated clockwise to elevate all of the plungers preliminary to a registering operation and it is rotated back to its normal position before 25 raising the frame 45 to its disconnecting position. This may be done by any suitable means, and in the simplified actuating mechanism shown, a hand crank 89 is provided on the end of the shaft for this purpose.

30 By the use of this aligning device in combination with the other mechanism that has been described, the entire operation of the registering mechanism is made positive so that the only chance of error is by reason of the machine being out of order altogether, or else by breaking something.

35 The spring operated aligning or spiral removing mechanism includes a series of 40 spring pressed levers 90 each having at its forward end a pointed nose 91 spring pressed against the head 82 of one of the stud bearings 52 of a gear 35. Said head 82 is made with a pointed or inverted V-shape 45 on its upper side, as shown in broken lines in Fig. 1, and when the supports 51 are in their normal middle position the point 91 of each lever 90 is pressed against the pointed upper part of a head 82. The points of said 50 lever and said head may be slightly rounded or flattened so that in the normal position the lever 90 has no tendency to displace the support 51 but if said support be slightly 55 displaced the pressure of the lever against the head 82 will tend to complete the movement.

60 The levers 90 are pivoted on a transverse rod 92 mounted at its ends in two frame plates 93 which are supported on the frame rods 55. In the form here shown the levers 90 are of the first order and their rear ends are drawn upward by springs 94 connected to a cross rod 95 secured in the frame plates 65 93. In the machine shown the right-hand frame plate 93 is not at the extreme right-

hand side of the machine and the first head 82 that is engaged by a lever 90 is that of the hundreds denomination, it being assumed that up to that point a spiral would not have developed to a sufficient extent to require correction. It will of course be understood that spring pressed devices performing the function of the levers 90 could be made to engage any convenient part of the supports 51. For the purpose of throwing 70 the levers 90 out of action and for bringing them into action successively, there is shown a shaft 96 journaled in the frame plates 93 and extending out to the right-hand side of the machine where it is provided with a hand crank 97. This shaft overlies the rear arms of the levers 90 and it is cut out along its length, but spirally, so as to produce one part 98 of full radius and another part 99 of less radius. The shaft normally stands 80 in the position shown in Fig. 1 with the part 98 depressing all of the levers 90 and rendering them inactive on the part 82. After the racks 12 have ceased to act on the register wheels, but while said wheels 90 are still in gear, the shaft 96 is turned to bring the low portion 99 thereof down, thus releasing the levers 90 to the action of their springs 94, and this turning of the shaft 95 releases said levers successively, beginning at the right of the series, owing to the spiral form of said shaft. The shaft is turned back to its Fig. 1 position after the register frame 100 has been turned up and, preferably, before the bail 74 is brought into action to restore the supports 51 so that said supports do not have to be restored against the resistance of the levers 90. In order to limit the motion of the crank 97, a stop 100 is shown consisting, in this instance, of the elongated head of one of the framing screws of the machine.

105 This spring-operated aligning mechanism is useful, but it would not by itself take the place of the plungers 83, because the latter 110 perform the additional function of locking the wheels in the register frame 45 while the said frame is in its raised position. This 115 spring-operated aligning mechanism may be omitted altogether, if preferred.

120 Various changes may be made in the details of construction and arrangement without departing from the invention.

125 What I claim as new and desire to secure by Letters Patent, is:

1. In a calculating machine, the combination of a series of drivers one for each denomination, a series of register wheels, a series of transmitting wheels one interposed between each register wheel and its driver and exterior to both, positively acting gearing whereby, during a registering operation the register wheel of one denomination bodily displaces the transmitting wheel of the next higher denomination to transfer, and 130

means for subsequently restoring any transmitting wheel so displaced.

2. In a calculating machine, the combination of a series of drivers one for each denomination and each provided with spur gearing, register wheels, having the form of spur gears, intermediate spur gears, each engaged on opposite sides thereof by one of said drivers and one of said register wheels, individual movable supports for said intermediate gears, means whereby during a registering operation one of said register wheels positively moves the support of next higher denomination to transfer, means for breaking the gear train, and means acting while said gear train is broken for restoring any supports that may have been moved as afore-said.

3. In a calculating machine, the combination with controlling mechanism, of registering mechanism comprising denominational wheels, a wheel of each denomination receptive to transfer being mounted on an individual back-and-forth-movable support, intermittent gearing whereby a wheel of one denomination positively moves the support of a wheel of another denomination in one direction to transfer during a computing operation, and means for restoring the displaced support between computing operations.

4. In a calculating machine, the combination with controlling mechanism, of registering mechanism comprising denominational wheels, a wheel of each denomination receptive to transfer being mounted on an individual back-and-forth-movable support, an intermittently acting positive connection from a wheel of one denomination to the movable support of a wheel of another denomination whereby the first recited wheel positively displaces the support of the second to transfer during a computing operation, and means for restoring the displaced support between computing operations.

5. In a calculating machine, the combination with controlling mechanism, of registering mechanism including wheels rotatable one way for addition and the other way for subtraction, a wheel of each denomination receptive to transfer being mounted on a reciprocatable support, intermittently acting positive means whereby a wheel of one denomination when turning one way forces the support of a wheel of another denomination in one direction and when turning the other way forces said support in the opposite direction; and means for restoring said support between computing operations.

6. In a calculating machine, the combination with controlling mechanism, of registering mechanism including wheels rotatable one way for addition and the other way for subtraction, a wheel of each denomination receptive to transfer being mounted

on a reciprocatable support, intermittent gearing between a wheel of one denomination and the reciprocatable support of a wheel of another denomination whereby the first recited wheel when turning one way forces said support in one direction and when turning the other way forces said support in the opposite direction; and means for restoring said supports between computing operations.

7. In a calculating machine, the combination with controlling mechanism, of registering mechanism comprising wheels rotatable one way for addition and the other way for subtraction, a wheel of each denomination receptive to transfer being mounted on a movable support which normally occupies a middle position, means whereby a wheel of one denomination when turning one way causes said support to be displaced in one direction from normal position and when turning the other way causes said support to be displaced in the opposite direction from normal; and means for restoring said supports from either displaced position to normal middle position.

8. In a calculating machine, the combination of a series of denominational racks, transmitting wheels each constantly in gear with a rack, individual movable supports for certain of said transmitting wheels, carrying wheels, means for moving said carrying wheels into and out of gear with said transmitting wheels, means acting on occasion while said carrying wheels are in gear to move one of said supports and thereby to impart to a carrying wheel an increment of motion to transfer, and means for restoring displaced supports while said carrying wheels are out of gear.

9. In a calculating machine, the combination with actuating devices, of a series of transmitting wheels, a series of individually pivoted sectors to which certain of said transmitting wheels are journaled, carrying wheels actuated by said transmitting wheels, intermittent gearing from a carrying wheel of one denomination to the sector of another denomination whereby said sector may be rocked about its pivot to transfer, means for breaking the gearing between said carrying wheel and said sector, and means for then restoring said sector.

10. In a calculating machine, the combination with actuating devices, of a series of transmitting wheels, a series of individually pivoted sectors to which certain of said transmitting wheels are journaled, carrying wheels actuated by said transmitting wheels, intermittent gearing from a carrying wheel of one denomination to the sector of another denomination whereby said sector may be rocked about its pivot to transfer, means for moving said carrying wheels out of gear with said transmitting

wheels and said sectors, and means for restoring said sectors while said carrying and transmitting wheels are out of gear.

11. In a calculating machine, the combination of a series of denominational racks, a series of transmitting wheels geared to said racks, individually pivoted sectors to which certain of said wheels are journaled, a series of carrying wheels adapted to gear with said transmitting wheels and each having part of an intermittent gear train, Geneva wheels constituting the other parts of said intermittent trains, gear wheels alternating with said carrying wheels, said gear wheels operated by said Geneva wheels and operating said sectors and means for restoring any sector to a normal position after each transfer involving that sector.

12. In a calculating machine, the combination of a series of denominational racks, a series of transmitting wheels geared to said racks, individually pivoted sectors to which certain of said wheels are journaled, a series of carrying wheels adapted to gear with said transmitting wheels and each having part of an intermittent gear train, Geneva wheels constituting the other parts of said intermittent trains, and gear wheels coaxial with said carrying wheels, said gear wheels operated by said Geneva wheels and meshing with and operating said sectors.

13. In a calculating machine, the combination of stationary framework, denominational racks mounted in said framework, a series of transmitting wheels geared to said racks, individual sectors pivoted in said stationary framework and to which certain of said wheels are journaled, a register frame, a series of carrying wheels in said register frame, said frame being movable into and out of operative position where said carrying wheels are in gear with said transmitting wheels, each of said carrying wheels having part of an intermittent gear train, Geneva wheels mounted in said register frame and constituting the other parts of said intermittent trains, gear wheels mounted in said register frame and alternating with said carrying wheels, said gear wheels operated by said Geneva wheels and operating said sectors when said register frame is in operative position, said sectors capable of being restored to normal position while said register frame is in inoperative position.

14. In a calculating machine, the combination of a series of register wheels, a series of transfer devices, and aligning mechanism including a series of aligning devices and means for operating said aligning devices successively, each of said aligning devices when operated acting on a register wheel and also on a transfer device.

15. In a calculating machine, the combination with stationary framework, and a register frame movable into and out of

operative position, of register wheels in said register frame, racks and transfer devices in said stationary framework, devices in said register frame for aligning said transfer devices while said register frame is in operative position, and means for restoring said transfer devices to normal while said register frame is out of operative position.

16. In a calculating machine, the combination with stationary framework, and a register frame movable into and out of operative position, of register wheels in said register frame, toothed devices in said stationary framework and adapted when said register frame is in operative position to actuate said register wheels differentially, means for imparting a units motion on occasion to any of said toothed devices to transfer, and devices in said register frame for aligning said toothed devices while said register frame is in operative position, said toothed devices being free of said aligning devices when said register frame is in operative position.

17. In a calculating machine, the combination with stationary framework, and a register frame movable into and out of operative position, of register wheels in said register frame, racks and transmitting wheels in said stationary framework, the latter meshing with said register wheels when said register frame is in operative position, means for displacing on occasion any of said transmitting wheels to transfer, devices in said register frame for aligning said transmitting wheels while said register frame is in operative position, and means for restoring any displaced transmitting wheel while said register frame is in inoperative position.

18. In a calculating machine, the combination of a series of denominational racks, a series of transmitting wheels geared to said racks, register wheels movable into and out of engagement with said transmitting wheels, transfer devices acting on occasion to displace a transmitting wheel to transfer, aligning devices for aligning said register wheels and said displaceable wheels while said register wheels are in gear, and means for restoring any displaced transmitting wheel while said register wheels are out of gear.

19. In a calculating machine, the combination of a series of denominational racks, a series of transmitting wheels geared to said racks, individually pivoted segments to which certain of said wheels are journaled, and register mechanism movable into and out of gear with said transmitting wheels and segments, said mechanism including a series of carrying wheels adapted to gear with said transmitting wheels and each having part of an intermittent gear train,

- Geneva wheels constituting the other parts of said intermittent trains, gear wheels alternating with said carrying wheels, said gear wheels operated by said Geneva wheels and operating said segments, and aligning devices acting while said register mechanism is in gear to align said carrying wheels and said alternating wheels and acting while said registering mechanism is out of gear to lock said carrying and alternating wheels. 5
20. In a calculating machine, the combination with a series of denominational devices, of aligning mechanism comprising a series of plungers each having therein an opening with two opposing concave walls, each shaped in the arc of a circle and said circles being eccentric to each other, and a rock shaft passing through said opening and having spirally arranged eccentric parts in 15 said opening, each of said eccentric parts when passing from one of said walls to the other operating to move its plunger a distance equal to the distance between the two said centers whereby said plungers are operated successively. 25
21. In a calculating machine, the combination with a series of toothed denominational devices, of a series of aligning plungers each slidable toward one of said denominational devices to engage and align the same and away from said device out of engagement, each of said plungers having an opening, two walls of which consist of arcs of circles whose centers are a distance 30 apart equal to the sliding motion of the plunger, a rock shaft passing through said openings and having its axis in one of said centers when the plungers are in engagement and in the other of said centers when 35 said plungers are out of engagement, and spirally arranged eccentric parts on said shaft and engaging in said openings. 40
22. In a calculating machine, the combination of a series of racks, a series of transmitting wheels geared to said racks, a series of register wheels geared to said transmitting wheels, supports for said transmitting wheels certain of said supports including a swinging member to which said wheel is 45
- journaled, and stationary plates to which 50 said members are pivoted, said plates being mounted on cross bars of the machine and each extending opposite one of said racks and transmitting wheels. 55
23. In a calculating machine, the combination of a series of racks, a series of register wheels, a series of transmitting wheels between said racks and register wheels, pivoted supports for certain of said transmitting wheels, means for swinging said supports to transfer, framework including a series of individual hangers to which said supports are pivoted, and frame bars on which said hangers are supported. 60
24. In a calculating machine, the combination with registering mechanism including a series of denominational devices, of aligning mechanism including a series of spring pressed devices, and means for normally holding said spring pressed devices 65 out of action and for releasing said devices to the action of their springs one after another. 70
25. In a calculating machine and in registering mechanism, the combination of a series of wheels, supports for said wheels displaceable to transfer, a series of spring pressed devices adapted to act on said supports to align them but normally held against the action of their springs, and 75 means for releasing said devices to the action of their springs one after another. 80
26. In a calculating machine, the combination with register wheels, of transfer mechanism including transmitting gears 85 each displaceable in its plane of action to transfer, movable supports for said wheels, spring pressed aligning devices for said supports, and means for holding said aligning devices against the action of their 90 springs and for releasing them to the action of their springs one at a time. 90

Signed at the borough of Manhattan, city of New York, in the county of New York and State of New York this 18th day of October, A. D. 1922. 95
